BAG HOLDER

Joseph A. Novatka, Cutchogue, N. Y.

Application September 10, 1941, Serial No. 410,344

2 Claims. (Cl. 248—99)

This invention relates to a bag holder which is mainly designed for use with a potato grader for holding bags so that the potatoes from the grader will pass into the bags and the invention is also mainly designed for use with paper bags.

The general object of the invention is to provide a supporting frame at the delivery end of the grader having means for holding the open end of a bag in spread out condition so that the potatoes will pass into the bag, with manually operated means for adjusting the holding means.

This invention also consists in certain other features of construction and in the combination and arrangement of the parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a top plan view showing a pair of bag holding means.

Figure 2 is an elevational view showing the device holding the bag with the bag in section.

Figure 3 is a section on the line 3—3 of Figure 1.

Figure 4 is a similar view showing the parts in inoperative position.

Figure 5 is a top plan view of one of the bag engaging means with the hangers in section.

Figure 6 is a fragmentary view of one of the outer side members of the frame with the groove member thereon for engaging a hand lever.

Figure 7 is a fragmentary view of the hand lever with the bracket attached thereto.

Figure 8 is a view of one of the crank shafts.

In these drawings the numeral 1 indicates a pair of frame bars which are connected to the rear ends of the frame A of a grader and when the device is to be constructed to hold two bags then a third bar 1' is connected to the central part of the rear end of the frame A between the bars 1 as shown in Figure 1. A pair of crankshafts 2 are journaled in the center bar 1' and one of the outer bars 1 and a second pair of crankshafts 2' is journaled in the other outer bar 1 and the center bar 1'. A pair of hangers 3 is adjustably connected to each shaft 2 by a bolt or screw 4, these hangers being spaced apart on the shaft and extend downwardly therefrom. An arcuate-shaped bar 5 is connected to the lower ends of each pair of hangers, the outer face of the bar 5 having a strip 6 of rubber or the like connected there-

with. One of the shafts of each pair is provided with a crank end as shown at 7, while the adjacent end of the other shaft is provided with a hanger 7' extending downwardly from the shaft and located outwardly of the outer bar 1. A hand lever 8 is provided for operating each pair of shafts, the inner end of the handle being connected to the central part of a bracket 9 with a link 10 pivotally connected to one end of the bracket with its other end pivoted to an intermediate part of the inner portion of the crank 7, as shown at 11. A second link 12 has its inner end pivotally connected to the other end of the bracket 9 and its outer end is pivotally connected to the hanger 7' of the other shaft 2 as shown at 13. The link 12 is formed with a plurality of holes 14 for selectively receiving the pivot 13 so that the parts can be adjusted for different sizes of bags. A bracket 15 is fastened to the central part of the outer face of each outer bar 1 and has a groove 16 therein which slopes downwardly and inwardly toward the frame A as shown more clearly in Figure 6. A bushing 17 of semi-circular shape in cross section is fastened to the lower end of the handle and operates in the groove 16 and a long bolt 18 passes through the bar 1 and the bracket 15, also through the central part of the bushing 17 and through the lower end of the handle as well as through the bracket 9, and a spring 19 is placed on the outer portion of the bolt and bears against the bracket 9 and against a nut 20 threaded on the outer end of the bolt.

Thus the bushing 17 engaging the groove 16 will hold the handle in the position shown in Figures 1 and 2 and in this position of the parts the shafts 2 are turned to cause the members 5 to spread the bag at its open end as shown in Figure 2. Then when the bag is to be released the handle 8 is swung upwardly and to the left in Figures 1 and 2 which will cause the shafts to be turned in an opposite direction and thus move the members 5 toward each other so as to release the bag. Of course, when the handle 8 is moved upwardly and to the left the bushing 17 will ride out of the groove 16 and upon the edges of the bracket 15 forming the groove, the spring 19 permitting this and when the hand lever is moved to its original position the spring will cause the bushing 17 to enter the groove 16 to hold the parts in bag holding position.

The inner ends of the shafts are held in the

member 1' by cotter pins 21 as shown more particularly in Figures 3 and 4.

While the device is mainly intended for a potato grader it will, of course, be understood that it can be used for holding the bag in any situation and in this case it would simply be supported by a stand.

It is thought from the foregoing description that the advantages and novel features of the invention will be readily apparent.

It is to be understood that changes may be made in the construction and in the combination and arrangement of the several parts provided that such changes fall within the scope of the appended claims.

Having described the invention, what is claimed as new is:

1. A bag holding device comprising a frame, a pair of spaced shafts rotatably supported by the frame one end of one of said shafts having a crank and the adjacent end of the other shaft having a hanger, a pair of hangers connected with an intermediate portion of each of the shafts, arcuate members connected with the lower ends of the intermediate hangers for engaging the inner walls of a bag at the open end thereof for spreading the open end of the bag, a handle pivoted to a part of the frame, a bracket

carried by the handle, a link connected to one end of the bracket and to the crank and a second link connecting the other end of the bracket to the first-named hanger.

5. 2. A bag holding device comprising a frame including parallel side members, a pair of spaced shafts having their ends rotatably arranged in the side members, hangers depending from an intermediate portion of the shafts, an arcuate member connected to the lower ends of the hangers of each shaft, a crank at the outer end of one of the shafts, a hanger on the outer end of the other shaft, a lever, a bracket connected at its center to the lower end of the lever, a link 10 connecting one end of the bracket with the crank, a link connecting the other end of the bracket with the last-named hanger, a second bracket connected to one of the side members and having an inclined groove therein, a semi-circular bushing connected to the lower end of the lever and normally fitting in the groove, a bolt passing through the side member, also through the second bracket, the bushing and the lower end of the lever, and a spring on the outer part of the bolt 15 with a nut on the outer end of the bolt for holding the spring in position.

JOSEPH A. NOVATKA.
